US0D1000375S

(12) **United States Design Patent** (10) Patent No.: **US D1,000,375 S**
(45) Date of Patent: ** Oct. 3, 2023

(54) **RECHARGEABLE BATTERY**

(71) Applicant: **Hilti Aktiengesellschaft**, Schaan (LI)
(72) Inventors: **Tobias Koeniger**, Bregenz (AT);
Johannes Hammers, Schaan (LI);
Andreas Spomer, Munich (DE); **Julian Winckler**, Feldkirch (AT); **Graham Keevy**, Aalen (DE)

(73) Assignee: **Hilti Aktiengesellschaft**, Schaan (LI)

(**) Term: **15 Years**

(21) Appl. No.: **29/853,193**

(22) Filed: **Sep. 14, 2022**

Related U.S. Application Data

(62) Division of application No. 29/775,221, filed on Mar. 22, 2021, now Pat. No. Des. 974,288.

(30) **Foreign Application Priority Data**

Sep. 23, 2020 (LI) 2020-696

CLAIM

The ornamental design for a rechargeable battery, as shown and described.

DESCRIPTION

FIG. 1 is a perspective view thereof;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view thereof; and,

FIG. 9 is a right side view thereof.

1 Claim, 9 Drawing Sheets
